UNITED STATES PATENT OFFICE.

JEAN PIERRE GELAS, OF ST. ETIENNE, FRANCE.

DESIGN FOR A PATTERN FOR TEXTILE FABRICS.

SPECIFICATION forming part of Design No. 22,181, dated January 31, 1893.

Application filed November 28, 1892. Serial No. 453,425. Term of patent 3½ years.

To all whom it may concern:

Be it known that I, JEAN PIERRE GELAS, of St. Etienne, Department of Loire, France, have invented and produced a new and original 5 Design for a Pattern for Textile Fabrics, of which the following is a specification, reference being had to the accompanying drawing, forming a part thereof.

The pattern shown is intended for button 10 stock.

The figure is a plan view of a strip of button stock showing my design.

The leading feature of my design is the 15 button-like figure produced upon the button stock, and consisting of the parallel strand-like figures having a braided or twisted appearance, and the band-like figures crossing the strand-like figures.

The button stock 10 has produced at inter- 20 vals thereon the figures 11, which simulate

somewhat a button, these figures being composed of parallel strands 12, the middle strands having a braided, and the outer strands a twisted appearance, and the cross band-like figures 13, which apparently pass over and 25 under the strand-like figures 12. The band-like and strand-like figures are produced in low relief, and the rectangular squares formed by the intersecting band-like and strand-like figures are given a broken or plaid like appearance, and they serve as a background for the strands and bands. 30

I claim—

The design for a pattern for textile fabric herein shown and described.

JEAN PIERRE GELAS.
